(57) **CLAIM**

The ornamental design for a playing surface assembly for spinning top toy, as shown and described.

DESCRIPTION

FIG. 1 is a front elevational view of the playing surface assembly for spinning top toy, showing the new design;

FIG. 2 is a left-side elevational view thereof;

FIG. 3 is a rear elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front, right-side, top disassembled perspective view, showing a state of being separated into four upper fasteners, a cover, a base, four lower fasteners, and a leg;

FIG. 10 is a rear, left-side, bottom disassembled perspective view, showing a state of being separated into the four upper fasteners, the cover, the base, the four lower fasteners, and the leg;

FIG. 11 is a cross-sectional view taken along the line 11-11 in FIG. 5;

FIG. 12 is a cross-sectional view taken along the line 12-12 in FIG. 5;

FIG. 13 is an enlarged detail perspective view of one of the upper fasteners shown disassembled in FIGS. 9 and 10;

FIG. 14 is another enlarged detail perspective view of one of the upper fasteners shown disassembled in FIGS. 9 and 10;

FIG. 15 is an enlarged detail perspective view of one of the lower fasteners shown disassembled in FIGS. 9 and 10;

FIG. 16 is another enlarged detail perspective view of one of the lower fasteners shown disassembled in FIGS. 9 and 10;

FIG. 17 is an enlarged detail perspective view of the leg shown disassembled in FIGS. 9 and 10; and,

FIG. 18 is another enlarged detail perspective view of the leg shown disassembled in FIGS. 9 and 10.

1 Claim, 15 Drawing Sheets
